UNITED STATES PATENT OFFICE.

JOHN ORMEROD, OF CASTLETON, NEAR MANCHESTER, ENGLAND.

MACHINE FOR DRESSING HIDES, SKINS, AND THE LIKE.

1,117,227.

Specification of Letters Patent. Patented Nov. 17, 1914.

Application filed October 28, 1913. Serial No. 797,725.

To all whom it may concern:

Be it known that I, JOHN ORMEROD, a subject of the King of Great Britain and Ireland, residing at Globe Leather Works, 5 Castleton, near Manchester, in the county of Lancaster, England, tanner, have invented new and useful Improvements in Machines for Dressing Hides, Skins, and the like, of which the following is a specification.

My invention relates to machines for dressing hides or skins for the purpose of unhairing, scudding, fleshing, setting and other analogous purposes, of the type in 15 which the skins are carried upon an endless traveling apron and in their passage through the machine are acted upon by a pair of cylinder knives each rotating on its axis in an opposite direction to the other, 20 one of such knives being placed at each side of a pair of grip rollers.

In machines at present in use the cylinder knives are carried by swinging counterbalanced arms and are brought to bear upon 25 the hide or skin by means of treadle mechanism at each side of the machine, necessitating two operators; the traveling bed being supported by rollers in fixed bearings.

In my invention I mount the cylinder knives 30 in fixed bearings and the supporting rolls for the traveling bed in adjustable slide bearings operated by levers and wedges and with the object of obtaining more accurate and easy regulation between the cylinder 35 knives and supporting rolls, than could be got with heavy cylinder knives rotating at high speeds and requiring regulation.

In the accompanying drawings, illustrating 40 my invention, Figure 1 shows a side elevation of the apparatus. Fig. 2 is a cross section. Fig. 3 is a plan view.

In a form of apparatus for carrying my invention into effect and which I now think suitable, I mount each of the cylinder knives 45 a, b in fixed bearings in the framework A of the machine. I also arrange a roller c, d below each cylinder knife a, b , the apron or bed e passing over such rollers, and between the rollers and the cylinder knives, 50 the bearings f, f' for the rollers c, d resting

on compression springs f^2 adjusted by set screws f^3 (see Fig. 1). The apron or bed e also passes around a roller g mounted in bearings g' slidable in the frame h the adjustment of the bearings g' to maintain the 55 apron taut being effected by screws h' . Means are provided to adjust the rollers c, d toward and away from the cylinder knives a, b so that the apron or bed e can carry the hide with any required degree of pressure 60 against the cylinder knives a, b .

The bearings f of the roller c are carried in side frames i formed in one with or connected to slides i^* and a treadle mechanism is used to adjust the roller 65 c toward and away from the cylinder knife. The treadle j by means of a lever j' , when depressed rocks a shaft j^2 which, by means of a lever j^3 , raises or lowers the slides i^* and with it the frames i . The bearings f' 70 of the rollers d are mounted in end frames i' , and the bearings k' of the under grip roller k are mounted in end frames m^2 . These end frames i' and m^2 are formed in one with or connected to slides B resting 75 upon a block C with an inclined under surface, the bars m, m^3 serving as guides for the slides B . The block C rests upon the inclined surface of the slide m' . The slide m' can be moved to and fro to adjust the 80 rollers d and k by means of a lever or crank n fixed to a shaft n^2 which shaft is rocked by a hand lever n' disposed at the same side as the treadle mechanism referred to above. The lower grip roller k and the roller d are 85 capable of yielding against the coiled springs k^2 and f^2 respectively and all the rollers c, d and k have adjusting screws f^3 to set the rollers and apron to a nicety and in true alinement toward the cylinder knives 90 a, b and upper grip roller o .

Adjustable stops f^4 are used to limit the upward movement of the rollers c, d and k .

By means of the adjusting set screws and the lever n' and wedge m' an exceedingly 95 fine and easy regulation is obtained to suit various thicknesses of skins, so that the lightest and most delicate skins may be operated on without damage to them.

The rollers c, d, k , beneath the cylinder 100

knives *a*, *b* may be covered with rubber, leather, felt or the like and the endless traveling apron *e* may be of soft rubber, leather or felt.

5 As the treadle and hand lever are each disposed at the same side of the machine, one operator is sufficient to work the apparatus.

10 A fault found with other machines of this type is the liability of the skins to warp around the upper grip roll *o*, and to adhere to the traveling apron *e* when they should leave the machine. To obviate this I provide the machine with a "doctor" blade 15 or stripping appliance *o'* bearing against the upper grip roll *o* and carried by a pivoted holder *o*² connected to a spring *o*³ which tends to pull the doctor against the roll *o*. A rotary brush *p* is used to insure the removal 20 of the skin from the apron *e*. This brush is carried in pivoted bearings *p'* and forced up to the apron by springs *p*².

With my machine it is found that the passage of the skin once through the machine 25 is sufficient.

Any suitable driving means are provided to drive the cylinder knives at high speeds in reverse directions, and the apron at the requisite slow speed. The driving means 30 used by me and considered so far as being suitable are indicated in the drawings.

The cylinder knives *a*, *b* have each a pulley *a'*, *b'* so that the knives can be revolved by belts from a countershaft; one belt being open and the other crossed.

40 The apparatus is provided with a main driving shaft *q* driven by a belt from a countershaft, on a pulley *q'*. The requisite slow motion from the driving shaft *q* to the roller *g* of the feed apron is obtained by the train of gearing *r*, *r'*, *r*², *r*³, *r*⁴, *r*⁵, *r*⁶ as shown in Fig. 1, this train of gearing having interchangeable parts to enable the speed of the apron to be varied. The brush 45 *p* is driven from the roller *g* by a chain *s* and chain wheels *s'*, *s*². The bottom grip roller *k* is driven from *g* also by a chain *t* and chain wheels *t'*, *t*². The upper grip roller *o* may be frictionally driven by the 50 apron or positively by a spur pinion on the axis of the lower grip roller gearing with a spur pinion on the axis of the upper grip roller. The rollers *c*, *d* are frictionally driven by the apron *e*.

55 The invention may be varied in mere point of detail.

The cylinder knives *a*, *b* are of the usual or convenient kind and when the machine is used for "fleshing" instead of knives having plain edges I may use knives in which the blades are serrated or saw toothed.

60 When the skin is first started in the machine the roller *c* is not brought up to the cylinder knife *a*, as this is revolving in a direction contrary to the traverse of the

skin, but the skin is fed to the grip rolls *o*, *k*. The grip rolls *d*, *k* are then raised by the hand lever to start the machine and when the leading end of the skin reaches the revolving cylinder knife *b* it begins immediately to act upon the skin, the cylinder knife *a* doing no work, all the work on the skin being done by the knife *b*. Assuming that the distance from the center grip rolls *o*, *k* to the knife *b* is six inches, before the 70 last six or seven inches of the skin pass under the knife roll *a*, the operator works the foot treadle and brings up the grip roll *c* to the knife *a*. The last six inches of the skin are then acted upon by the knife *a* 75 and as soon as the end of the skin is released by the center grip rolls *o*, *k* the knife *b* cannot act on the skin, as it is not held by said grip rolls, and the knife *b* simply flicks the skin out of the machine. The 80 whole of the skin has thus been acted upon once only, which is essential to attaining perfect results especially when working on delicate skins.

I declare that what I claim is:

90 1. In apparatus for treating hides and skins for the purpose of unhairing, scudding, fleshing, setting or the like, a pair of revolving cylinder knives, fixed bearings in which such knives can revolve, a pair of 95 grip rollers disposed between the revolving cylinder knives, a grip roll arranged beneath each cylinder knife, an apron carried upon an adjustable roller and upon the grip rolls beneath the cylinder knives and 100 the lower of the pair of central grip rolls, and independently actuated means for carrying the apron up to and away from each revolving cylinder knife substantially as described.

105 2. In apparatus of the indicated kind a pair of rotatable cylinder knives mounted in fixed bearings, an apron *e* carried on grip rollers *c*, *d*, *k* and on a roller *g*, means to regulate the tension of the apron and for 110 driving same, and independently actuated means consisting of a foot treadle and a hand lever arranged at the same side of the machine for carrying the apron up to and away from either of the cylinder knives substantially as described.

115 3. In apparatus of the indicated kind, a pair of cylinder knives mounted in fixed bearings, means to drive the cylinder knives in reverse directions, an upper grip roller *o*, 120 an apron *e* carried on grip rollers *c*, *d*, *k* and on a roller *g*, means to regulate the tension of the apron and for driving same, independently actuated means for carrying the apron up to and away from the upper 125 grip roller *o* and up to and away from one of said cylinder knives, independently actuated means for carrying the apron up to and away from the other of said cylinder knives, bearings for the rollers *c*, *d*, *k* hav- 130

ing compression springs, set screws to adjust such springs, a doctor blade *o'* for preventing the skin or hide from wrapping around the grip roller *o* and a brush *p* for preventing the skin from adhering to the apron substantially as described.

In testimony whereof I have signed my

name to this specification in the presence of two subscribing witnesses.

JOHN ORMEROD.
